MEGAPHONE

Harrison L. Staley, Martinsville, Ind.

Application March 7, 1932. Serial No. 597,165

6 Claims. (Cl. 181—27)

My improvement relates to means for conducting all the sounds of the voice emitted from both the mouth and nose into the megaphone so that it will produce clearer and louder amplification.

In types of megaphones heretofore produced, the receiving end into which the voice is introduced has been shaped to cover only the mouth. Such an arrangement eliminates entirely from the amplifying chamber the resonant sounds of the nasal cavity and these sounds I have found are necessary to the proper amplification of the voice.

In my experimentation, I have discovered that in normal position the receiving end of the megaphone should be held closely over the mouth and, that by introducing into the megaphone the sounds projected by the nose while in this position, naturalness of the voice is maintained and the volume and carrying power greatly increased without any additional strain on the vocal cords.

I have discovered further, that if provisions are made in the megaphone for the proper introduction of the nasal sounds, there is no conscious effort of the user to force the sound through the mouth only, an effort that usually lifts the soft pallet and robs the amplified voice of its true power and clarity.

It is therefore the object of my invention to produce a megaphone into which the sounds from both the mouth and nose shall be introduced simultaneously in such a manner that there shall be no loss to the force of the sound waves. To this end, reference is made to the following drawing which illustrates the embodiment of my invention.

Figure 1 is a perspective view of the megaphone showing the preferred arrangement of my invention. Figure 2 is a fragmentary section of the megaphone showing a side view of the receiving end. Figure 3, a top view of the receiving end. Figure 4 is a modification of the megaphone.

The body A of the megaphone is hollow, preferably conical in shape and constructed of thin papier-mâché, metal or other suitable material, with both ends open, the larger end B for projecting the amplified sound and the smaller end C for receiving the sound from the voice. Attached to the receiving end C is a mouth piece D which is composed of two elements E and F. It is preferred that the mouth piece D be constructed of metal and have a beaded edge to protect the user from injury when the megaphone is brought into normal position against the face.

Element E of the mouth piece D should be cir-

cular and shaped so as to fit the contour of the mouth and the element F should be a forwardly closed hollow transverse projection and slightly V shaped to inclose the lower portion of the nose. I also prefer that the forward wall of element F be rearwardly inclined so that it will not interpose any obstruction to the forward movement of the sound waves coming from the nose.

It will thus be seen that the mouth piece D covers completely the openings of both the mouth and nose and that any sound emitted therefrom is carried simultaneously into the receiving end of the megaphone.

It is obvious that elements E and F of the mouth piece D can be made in one piece of suitable material and attached to the body A by any practical means or, if made of papier-mâché, they can be moulded integrally with the body A itself.

Instead of having element F project above the body A as in Figure 1, the mouth piece D can be made large enough to cover both the nose and mouth, and be provided with a notch G forwardly formed in the mouth piece D to permit the lower portion of the nose to be inclosed in the receiving end of the megaphone. This modification is clearly shown in Figure 4.

Details of this nature are immaterial. My invention has for its purpose the carrying into practice of my discovery that to produce a megaphone that will amplify the voice with great volume and clarity without undue strain on the vocal cords, means must be provided in the receiving end of the megaphone for introducing all the sounds emitted from both the mouth and nose into the amplifying chamber of the megaphone.

I am fully aware that, if the receiving end C of the megaphone is made large enough, as in the present well known type of megaphone, and be held slightly forward of the mouth, the sounds coming from the nose will in part enter the mouth piece, but the mere fact that it is held forwardly of the mouth permits the escape and lessens the force of the sound waves to the extent that a very poor amplification of the voice occurs.

Having fully described my invention, I claim as new:

1. A megaphone comprising a conical tubular body having a smaller end so sized and shaped as to be contactable with the face of the user around and to closely encompass both the mouth and nasal passages, with the nasal outlets within the outwardly flaring interior of the main body.

2. A megaphone comprising a conical tubular

- body having at one side of its smaller end a trans-
verse nose-receiving notch permitting the entry
of the nose of the user into the outwardly flaring
interior of the tubular body.
5. A megaphone comprising a conical tubular
body having its smaller end sized to closely en-
compass the mouth, a transverse notch located
at one side of the smaller end of said body, and
an open end V shaped projection whose forward 80
wall is rearwardly inclined secured over said
transverse notch to encompass the nose, said
projection having an outlet within the outwardly
flaring interior of the tubular body, and to form
a mouth piece of one continuous opening for the
mouth and nose of the user.
6. A megaphone comprising an outwardly flar-
ing tubular body having its smaller end sized to
closely encompass the mouth, an opening in the
wall of said body located near its smaller end, 90
and means to connect the opening in the wall of
said body with the outlets of the nasal cavities of
the user, substantially as described.
- 25 4. A megaphone comprising a conical tubular
body having its smaller end sized to closely en-
compass the mouth, a transverse notch located
at one side of the smaller end of said body, an
open end V shaped enclosure for the nose pro-
jecting over said transverse notch, with the out-
let thereof located within the outwardly flaring
20 interior of the tubular body.
